1,964,325

SIGNALING MEANS

States Lee Lebby, Corning, N. Y., assignor to
Corning Glass Works, Corning N. Y., a corpora-
tion of New York

Application April 30, 1928, Serial No. 274,021

2 Claims. (Cl. 177—329)

This invention relates to the art of light pro-
jection and more particularly to an improvement
in signaling means.

In many prior types of signals considerable
difficulty has been experienced in securing a
sufficiently wide spread of the light rays to make
the signal visible when the person approaching
it is at a considerable angle from the axis there-
of. I have discovered that this can be overcome
by providing the cover glass for the signal with
a suitable arrangement of refracting flutes and
prisms.

It is therefore an object of this invention to
provide a new and improved signal.

It is a further object of this invention to pro-
vide a signal which will have a much greater
spread than any signal heretofore known.

It is also an object of the present invention to
provide a signal which refracts the light down-
wardly for a close-up indication in conjunction
with a wide lateral distribution of light.

It is a particular feature of this invention to
provide a cover glass which will produce an im-
proved light distribution.

With the above and other objects in view,
which will be apparent as the description pro-
ceeds, I have set forth my invention in the fol-
lowing specification and illustrated it in the ac-
companying drawings, in which:

Fig. 1 is an inside elevational view of my im-
proved cover glass;

Fig. 2 is a vertical section on the line 2—2
of Fig. 1;

Fig. 3 is a side elevation, partly in section, on
the line 3—3 of Fig. 1;

Figs. 4, 5 and 6 are diagrammatic views show-
ing the light distribution produced by my new
cover glass in combination with a suitable re-
flector, Fig. 4 being a vertical section on the line
4—4 of Figs. 5 and 6, Fig. 5 being a horizontal
section on the line 5—5 of Figs. 4 and 6, and
Fig. 6 being an inside elevational view showing
the light distribution from the side refracting
lenses.

Referring to the accompanying drawings, it
will be seen that my improved signal consists of
a reflector 8, a light source 9, and a cover glass
10, the light source 9 being shown as a point
light source for simplicity of illustration and
being placed at the common focal point of the
reflector and the cover glass.

As best shown in Figs. 1—3, my improved cover
glass 10 consists of a central convex body por-
tion 11 provided with a continuous, rearwardly-
extending conical flange 12. The front face 13

of portion 11 is preferably smooth, but its rear
face 14 is provided with a series of vertical flutes
15, each of which is of substantially semi-cylin-
drical cross-section.

Each flute 15 is also provided with a small flute 16
16, which increases in thickness from top to bot-
tom, the flutes 16 on one row of main flutes 15
being staggered with respect to the flutes 16 in
adjacent rows.

The main flutes 15 are provided to spread the 65
light horizontally, as shown in Fig. 5, the maxi-
mum rays from this portion of the signal being
designated A and A'. The small flutes 16 are
designed to produce a downward deflection of a
portion of the light for a close-up indication, as 70
shown by the rays B—B' in Fig. 4, produced by
the lower part of the cover glass, it being under-
stood that similar rays (not shown) are produced
by the upper part of the cover glass. The main
body of the light rays from the reflector 8 is 75
projected as a bundle of horizontally extending
rays. The portion of these rays transmitted by
the upper half of the cover glass is indicated dia-
grammatically in Fig. 4 by the rays C—C', and
a corresponding bundle of rays (not shown) 80
would be transmitted by the lower half of the
cover glass.

With the flutes 15 alone it would be difficult
to get an efficient spread of even 90°, but I have
found that by providing the inside of the flanged 85
portion 12 with a pair of side refracting lenses 18
it is possible to utilize a large angle of the direct
light source rays by refracting them into two
oppositely directed vertically concentrated bun-
dles, each of which is substantially unrefracted 90
in a horizontal direction, thus forming fan-
shaped beams of horizontally extending rays
D—D' and E—E' at substantially right angles to
the rays C—C'. These rays are produced by light
which would otherwise be lost but which I utilize 95
by directing them into wider spread angles of
the horizontal beam to produce an extension of
the spread to approximately 180°, thus giving
about 90° additional spread.

For some purposes, and as shown in Figs. 2—5, 100
I also prefer to provide the exterior of the flanged
portion 12 with a series of circular prisms 19
which extend all the way around the cover glass
and bend the light forwardly so that the maxi-
mum spread with the particular mirror and cover 105
glass shown is limited to 160°.

Although I have herein indicated the reflecting
means 8 as a mirror of the type shown and de-
scribed in my application Serial Number 36,514,
filed June 11, 1925, it should be understood that 110

the operation of my cover glass will be substantially the same as indicated above regardless of the type of mirror used, provided the focal point of the mirror, which is where the light source is placed, is coincident with the focal point of the cover glass. If this condition is satisfied the mirror can be of various types, such as parabola, a Mangin mirror, an aplanatic mirror, or any other mirror producing approximately parallel light.

10 It will be understood that in practice the light source 9 is a commercial lamp, but I have herein merely shown it as a point light source to avoid confusion in the diagrammatic illustration of the light rays. The only difference in the rays when produced by a suitable commercial light source and by a point light source is that with the former there is an overlapping of the light rays which would cause confusion in a diagrammatic showing.

20 It will therefore be apparent that I have produced a new and improved type of signal which gives a very wide lateral spread in addition to a close-up indication, and that my invention is susceptible of various modifications within the 25 scope of the following claims. If desired, my cover glass may be provided merely with the main flutes, or merely with the main flutes and smaller flutes on the front portion, and in certain other cases it may be desirable to utilize the side re-

fracting lenses without the main and smaller flutes, or to substitute other refracting media for the side refracting lenses, but to obtain maximum efficiency, especially for highway crossing signals, I prefer to utilize all of the refracting means set forth above. 80

I claim:

1. In an optical system a reflector for projecting a main beam of light and having its principal focus within the main beam, a fluted cover glass in the main beam for spreading the latter in one plane, a conical flange on the cover glass and light condensing members on the flange having a common focus which coincides with the focus of the reflector, the condensing members being so disposed with relation to the flutes on the cover glass that the beam projected thereby will join the main beam and form a continuation thereof without perceivable interruption. 85

2. In an optical system, the combination of a light source, a refracting cover glass having a conical flange, said flange having at the sides thereof prismatic light-condensing elements extending longitudinally of said flange and having a focal relationship with said light source, the 100 several condensing elements decreasing in width toward the smaller end of said conical flange. 90
